UNITED STATES PATENT OFFICE

2,554,384

FURNACE WALL CONSTRUCTION FOR GAS
OR OIL AND SOLID FUELGustav A. Rehm, Worcester, Mass., assignor to
Riley Stoker Corporation, Worcester, Mass., a
corporation of Massachusetts

Application October 23, 1947, Serial No. 781,689

6 Claims. (Cl. 110—1)

1

This invention relates to furnaces, and more particularly to furnaces for burning a fluent fuel such as gas or oil, and a solid fuel such as coal. Furnaces of this type have the advantage that either the fluent fuel or the solid fuel may be burned, as may be most economical in view of the prevailing market conditions.

One prior furnace construction for burning solid fuel comprises a furnace combustion chamber having a grate therein, and a spreader stoker for throwing fuel onto the grate through an opening in the front wall of the combustion chamber. The wall above the opening is usually supported by a horizontal beam. In order to permit firing such a furnace with fluent fuel, it has been proposed to provide a burner opening for the fluent fuel through the front wall above the beam. However, this brings the burner opening a considerable distance above the grate, and unless the combustion chamber is very high the flame will be too close to the roof of the chamber.

It is accordingly one object of the invention to overcome this difficulty and to provide a furnace construction which will permit the burner opening to be placed in a considerably lower position than in prior arrangements.

It is a further object of the invention to provide, in combination with a spreader stoker furnace, a new and advantageous construction for the front wall of the furnace, which will permit the introduction of fluent fuel through the wall at a relatively low elevation.

With these and other objects in view, as will be apparent to those skilled in the art, the invention resides in the combination of parts set forth in the specifications and covered by the claims appended hereto.

Referring to the drawings illustrating one embodiment of the invention, and in which like reference numerals indicate like parts,

Fig. 1 is a longitudinal vertical sectional view through the front portion of a furnace, taken on the line 1—1 of Fig. 4;

Fig. 2 is a section taken on the line 2—2 of Fig. 1, with the refractory portion of the wall removed;

Fig. 3 is a section taken on the line 3—3 of Fig. 2; and

Fig. 4 is a section taken on the line 4—4 of Fig. 1, with the oil burner removed.

The embodiment illustrated comprises a furnace front wall 10, two opposed side walls 11, and a roof 12. Upright water wall tubes 14 are provided adjacent to the side walls 11, the upper portions of these tubes being bent laterally to

2

extend beneath the roof 12 and support the same. The water wall tubes may form part of a steam generator of the general type disclosed in the patent to Kuhner No. 2,221,382, granted Nov. 12, 1940. A grate 15 is provided in the lower portion of the furnace, with an ash pit 16 beneath the grate. Access may be had to the ash pit through an opening 18 in the lower portion of the front wall, this opening having the usual ash door 19 associated therewith. The door 19 is mounted on an upright metal front plate 20.

Provision is made for supplying solid fuel to the grate 15, thereby forming a fuel bed in which combustion will take place. For this purpose an opening 22 is provided in the front wall 10 somewhat above the level of the grate, and a spreader stoker 23 is mounted in front of this opening. This stoker comprises a hopper 24 for a suitable solid fuel, such as crushed coal, a horizontal rotor 25 to throw fuel rearwardly through the opening 22, and a reciprocable ram 27 to feed fuel to the rotor from the bottom of the hopper.

The lower portion of the front wall 10, beneath the opening 22 and at the sides thereof, may rest on the foundation therebeneath. The portion of the wall above the opening 22 must be supported independently of the lower portion to avoid excessive weight on the latter, as well as other difficulties. For this purpose there is provided a horizontal beam in the form of a plate girder 29 spaced above the opening 22. This girder comprises a vertical plate or web 30 of considerable height, a horizontal plate 31 adjacent the upper edge of the web, and a horizontal plate 32 adjacent the lower edge of the web. The upper plate 31 is connected to the web by a pair of horizontally extending reinforcing members 34 of channel-shaped cross section located on opposite sides of the web. Similarly, the lower plate 32 is connected to the web by a pair of horizontally extending reinforcing members 35 of channel-shaped cross section located on opposite sides of the web. The ends of the girder 29 are suitably attached to two upright columns 36 which provide a support for the girder.

The upper margin of the fuel admission opening 22 is formed by an arch 38 which preferably extends horizontally from one side wall 11 to the other. This arch is formed by refractory blocks which are carried by metal brackets 40 of well known construction attached to the lower plate 32 of the girder 29.

Means is provided for introducing fluent fuel into the furnace through the front wall 10, to-

gether with the air necessary for combustion of such fuel. This requires an opening of considerable size, but by employing the girder 29 with its high web 30 it becomes feasible to provide this web with an opening 42 large enough for the required purpose. By this means the point of fuel introduction may be brought much lower than would otherwise be possible. The construction of the girder is such that it retains ample strength to support the wall. In the particular embodiment illustrated, the opening 42 is square and extends from the bottoms of the upper channel members 34 to the tops of the lower channel members 35. Within the opening 42 there is mounted a square burner box 43 which extends rearwardly beyond the web 30 and is provided with a transverse vertical plate 44 parallel with the web and having a large circular opening 46 therethrough. Within the rear portion of the box 43, behind the plate 44, there is installed refractory material 47 which defines a circular opening 48 in registration with the plate opening 46. The front portion of the box 43 is enlarged to provide an air chamber 50 to which air may be supplied under pressure from any suitable source through a duct 51. An oil burner nozzle 52 is mounted within the box 43 coaxial with the opening 46, and an air register 54 surrounds the nozzle to whirl the combustion air approaching the opening and direct it into proper contact with the oil spray in known manner.

To permit inspection of combustion conditions, openings 55 (Fig. 4) are provided in the front wall 10 adjacent to the side walls 11. These openings register with openings 57 in the web 30, the latter openings being provided with suitable doors 58.

In order to minimize the possibility of overheating the girder 29 and adjacent metal parts, provision is made for the natural upward circulation of cooling air between the girder and the refractory portion of the wall directly behind the same. For this purpose vertical passages 60 (Fig. 4) are provided on opposite sides of the burner box 43, the girders forming the front wall of each passage. The rear edges of the girder plates 31 and 32 are notched at 62 and 63 respectively (Fig. 3) in registration with these passages to permit the desired air flow. The front plate 20 is provided with openings 65 near its upper edge for the admission of air into contact with the brackets 40 and thence into the passages 60. Boxes 66 are mounted on the top of the girder to register with the upper ends of the passages 60 and permit the air therefrom to flow forwardly into the room.

It will now be apparent that the furnace may be fired either with solid fuel by means of the spreader stoker 23, or with oil by means of the burner 52. The girder 29 provides a strong and dependable support for the portion of the front wall 10 above the opening 22. Air entering the openings 65 under the action of natural draft will provide adequate cooling for the brackets 40 and the girder. By introducing the oil and

the combustion air therefor through the opening 42 in the girder web 30, it is possible to provide a flame comparatively close to the grate 15 and thus obtain better combustion conditions and less danger of flame impingement on the furnace roof 12.

Having thus described my invention, what I claim as new and desire to secure by Letters Patent is:

- 10 1. A furnace front wall construction comprising a lower upright wall portion of refractory material having an opening therethrough for the admission of solid fuel, a horizontal metal girder located somewhat above the opening, two horizontally spaced upright columns supporting the opposite ends of the girder, and an upper upright wall portion of refractory material located above the said lower wall portion and supported by the girder, the girder having an opening extending horizontally therethrough intermediate its ends and the upper wall portion extending behind the girder and having an opening in registration with the girder opening for the admission of fluent fuel in a rearward direction.
- 15 2. A furnace as set forth in claim 1, in which the girder comprises an upright web of considerable height, and the girder opening is provided through the web.
- 20 3. A furnace as set forth in claim 2, in which the girder comprises horizontal plates attached to the upper and lower edges of the web.
- 25 4. A furnace as set forth in claim 3, in which refractory blocks provide a horizontal arch forming the upper edge of the solid fuel admission opening, and in which metal brackets are attached to the bottom of the girder to support the said blocks.
- 30 5. A furnace as set forth in claim 4, in which horizontally extending reinforcing members are provided on both sides of the girder web adjacent to the upper and lower edges thereof.
- 35 6. A furnace as set forth in claim 1, in which the wall is formed with passages behind the girder for the natural upward circulation of air in cooling contact with the girder.

GUSTAV A. REHM.
